UNITED STATES PATENT OFFICE.

HAROLD ROWNTREE, OF KENILWORTH, ILLINOIS, ASSIGNOR TO NATIONAL PNEUMATIC COMPANY, OF CHICAGO, ILLINOIS, A CORPORATION OF WEST VIRGINIA.

PASSENGER-CAR.

1,172,563.

Specification of Letters Patent. Patented Feb. 22, 1916.

Application filed October 16, 1912. Serial No. 725,987.

To all whom it may concern:

Be it known that I, HAROLD ROWNTREE, a citizen of the United States, residing at Kenilworth, in the county of Cook, State of Illinois, have made a certain new and useful 5 Invention in Passenger-Cars, of which the following is a specification.

This invention relates to passenger cars.

The object of the invention is to provide 10 a passenger car which is simple in construction, and which is of the fare prepayment type, and wherein provision is made for a smoking compartment or a compartment adapted to contain the various mechanisms, 15 motors, etc., for operating the auxiliary devices of the car, or for affording space for amusement, advertising, entertaining, freight or other purposes, while at the same time affording ample seating accommodations for 20 the passengers to be carried.

Other objects of the invention will appear more fully hereinafter.

The invention consists substantially in the construction, combination, location and relative arrangement of parts, all as will be more fully hereinafter set forth, as shown in the accompanying drawings and finally pointed out in the appended claims.

Referring to the accompanying drawings:—Figure 1 is a view in side elevation of a passenger car embodying the principles of my invention. Fig. 2 is a horizontal sectional view, in floor plan, of the same. Fig. 3 is a view showing the application of my invention to a double deck car. In carrying out my invention I propose to employ a doorway in the side of the car but preferably at a point intermediate its ends, and specifically at a point adjacent one end 40 thereof, and controlled by suitable doors operated from a conductor's station within the car, or inside the doors, from which station the doors are opened and closed and fares of entering passengers are collected as 45 the passengers enter. At the extreme end of the car, adjacent to the conductor's station, I propose to provide an elevated auxiliary compartment designed to carry, and to afford a convenient storing space for the 50 various auxiliary mechanisms carried by the car, and which auxiliary compartment may

also serve the purpose of a space, if so desired, for giving performances for the entertainment of the passengers of the car, or, if desired may be utilized as a smoking compartment, for advertising or other purposes, 55 said auxiliary compartment being reached by a stairway leading from the platform or loading or unloading space adjacent to the doorway.

Referring to the accompanying drawing reference sign A, designates a passenger car. B, designates the trucks therefor. Adjacent one end of the car at one side thereof I propose to form a doorway designed to be 60 controlled by suitable doors C. These may be of any suitable or convenient type or construction and may be operated or controlled in any suitable or convenient manner, and either manually or by power mechanism, as may be desired. In the particular form shown, to which however, my invention is not to be limited or restricted, in the broadest scope thereof, as defined in the claims, I propose to employ folding doors 65 controlled by suitable doors C. These may be of any suitable or convenient type or construction and may be operated or controlled in any suitable or convenient manner, and either manually or by power mechanism, as may be desired. In the particular form shown, to which however, my invention is not to be limited or restricted, in the broadest scope thereof, as defined in the claims, I propose to employ folding doors 70 controlled by suitable doors C. These may be of any suitable or convenient type or construction and may be operated or controlled in any suitable or convenient manner, and either manually or by power mechanism, as may be desired. In the particular form shown, to which however, my invention is not to be limited or restricted, in the broadest scope thereof, as defined in the claims, I propose to employ folding doors 75 controlled by suitable doors C. These may be of any suitable or convenient type or construction and may be operated or controlled in any suitable or convenient manner, and either manually or by power mechanism, as may be desired. In the particular form shown, to which however, my invention is not to be limited or restricted, in the broadest scope thereof, as defined in the claims, I propose to employ folding doors 80 controlled by suitable doors C. These may be of any suitable or convenient type or construction and may be operated or controlled in any suitable or convenient manner, and either manually or by power mechanism, as may be desired. In the particular form shown, to which however, my invention is not to be limited or restricted, in the broadest scope thereof, as defined in the claims, I propose to employ folding doors 85 controlled by suitable doors C. These may be of any suitable or convenient type or construction and may be operated or controlled in any suitable or convenient manner, and either manually or by power mechanism, as may be desired. In the particular form shown, to which however, my invention is not to be limited or restricted, in the broadest scope thereof, as defined in the claims, I propose to employ folding doors 90 controlled by suitable doors C. These may be of any suitable or convenient type or construction and may be operated or controlled in any suitable or convenient manner, and either manually or by power mechanism, as may be desired. In the particular form shown, to which however, my invention is not to be limited or restricted, in the broadest scope thereof, as defined in the claims, I propose to employ folding doors 95 controlled by suitable doors C. These may be of any suitable or convenient type or construction and may be operated or controlled in any suitable or convenient manner, and either manually or by power mechanism, as may be desired. In the particular form shown, to which however, my invention is not to be limited or restricted, in the broadest scope thereof, as defined in the claims, I propose to employ folding doors 100 controlled by suitable doors C. These may be of any suitable or convenient type or construction and may be operated or controlled in any suitable or convenient manner, and either manually or by power mechanism, as may be desired.

In the arrangement shown the conductor's control stand D, is located at approximately 85 the midwidth of the car adjacent to the raised portion or platform E at the extreme end of the car. The conductor's station, however, may be on the lower floor portion F, of the seating space of the car and which seating space is provided with the ordinary or any usual or convenient arrangement of seats G, for the accommodation of passengers. Preferably the floor F of the seating space of the car is inclined or formed in a 90 ramp from the doorway or door C, toward the far or extreme end of the car so as to be eventually raised above the truck B at that end of the car. By this arrangement I am enabled to provide a stepless form of 95 car so that passengers may step directly from the street level into the floor of the

car through the door C. After paying their fare the passengers may then proceed to the seats G. On the opposite side of the car from the doorway controlled by the doors C, I provide a stairway H, leading from the level of the floor F of the seating space of the car to the elevated or raised compartment E. If desired a doorway and door J may be provided at the bend of the stairway H, to afford communication from said stairway to the auxiliary compartment E which is shown as located at a level above that of the floor of the car at the loading platform K. This compartment may be utilized as a smoking compartment, as a compartment for the storage of the various auxiliary appliances and mechanisms used or employed in connection with the operation of the car, or it may be employed for giving exhibitions or entertainments, for advertising purposes, for a lunch stand, for carrying freight, or for any other purpose desired. If desired this raised compartment may be provided with a doorway and a door in the side thereof, as indicated at R. This is a desirable feature where said compartment is employed for carrying freight.

It will be observed that the raised auxiliary compartment E, is at the front end of the car, and that all of the passengers in the body of the car or seating space thereof, face forwardly toward it. If desired, seats may be arranged in the auxiliary compartment E as indicated at M, for the accommodation of passengers where said compartment is used as a smoking compartment.

From the foregoing description it will be observed that the construction described affords a stepless car which is easy of access by passengers. It also is of the form of the fare prepayment type where entering passengers only pass in one direction while passing the conductor instead of passing in both directions as in the ordinary type of center entrance cars.

The provision of the auxiliary compartment E affords a suitable accommodation for smokers while at the same time it forms an available space for mechanism employed in connection with the auxiliary devices on the car and which on the ordinary type of car, and especially on the drop frame and stepless type, are almost entirely crowded into inaccessible spaces under the car or in the roof of the car. This is a very material matter of convenience since it facilitates access to the various devices, motors and the like, required in the operation of the car, for repairs or other purposes.

If desired the construction may be easily and readily converted into a double deck car by merely extending the stairway H to reach the upper deck.

The construction described combines within itself all of the advantageous fea-

tures of the end entrance car as well as the center entrance cars while eliminating the objectionable features of both.

If desired, a raised seat P may be provided adjacent the conductor's control stand D for the accommodation of the conductor or the seat may be placed on a level with the floor of the elevated compartment. This will afford an elevation of the conductor above the heads of entering passengers so as to enable him to maintain controlling observation of entering and leaving passengers, thereby avoiding danger of accidents while boarding and alighting from the car.

It will be understood that where the auxiliary compartment E is employed as a smoking compartment, said compartment will be separated from the balance of the body of the car by a partition indicated at R.

In the case of a double deck car, as indicated in Fig. 3, the stairway H delivers from the space K in front of the side doorway, to a landing R, on the floor level of the raised compartment E, and which opens into said compartment through a doorway and door indicated at S. From this landing a second stairway T, continues to the upper deck of the car.

Having now set forth the object and nature of my invention and a construction embodying the principles thereof, what I claim as new and useful and of my own invention and desire to secure by Letters Patent is:

1. A passenger car having a side entrance adjacent one end thereof, doors for controlling said entrance, a raised compartment for passengers in advance of and immediately adjacent said doorway, steps located opposite said doorway leading to said raised auxiliary compartment and means arranged within said doorway for controlling the operation of said doors.

2. In a passenger car, a car body having a seating space for passengers, a doorway and a door in the side of said car, adjacent one end thereof, a passenger compartment arranged on one side of said doorway and having an elevated floor, a stairway located opposite said doorway and leading to said raised compartment, and means for controlling the doors for the doorways, said means located inside said doorway and between the same and said stairway.

3. A passenger car having a car body with an interior seating space, a doorway in the side of said car body, adjacent one end thereof, an inclined floor leading from said doorway to the other end of said car, said inclined floor extending over the trucks at the rear end of the car, a raised platform at the extreme forward end of the car, a stairway located at the side of the car opposite the doorway therein, and leading to the raised compartment a door for said doorway and

means to control said door, said means located between the doorway and stairway.

4. A passenger car having a car body with an interior seating space, a side doorway located adjacent the front end thereof, a door for controlling said doorway, a raised auxiliary compartment at the extreme forward end of said car, an inclined floor for the seating space of the car leading from the doorway to a point over the truck at the rear end of the car, means for operating the door, said means located immediately at the rear of the raised auxiliary compartment, a stairway located at the opposite side of the car from the doorway thereof, and leading from the main body portion of the car to the raised auxiliary compartment, and a conductor's seat located at the door control means.

20 5. A passenger car having front and rear trucks, a car body having a front floor portion raised over the front trucks, a side doorway immediately adjacent the rear of the front trucks, the car body having a rear floor portion inclined from the doorway and extending over the rear trucks.

6. A passenger car having front and rear trucks, a car body having a front floor portion raised over the front trucks, the floor of the car body at the rear of the front trucks being within a single stepping distance of the ground level, and having a side doorway immediately at the rear of said front trucks, the rear portion of the floor extending in a ramp from the doorway to and over the rear trucks.

7. A passenger car having front and rear trucks, a car body having a front floor portion raised over the front trucks, a side doorway adjacent the rear of the front trucks, the car body having a rear floor portion inclined from the doorway and extending over the rear trucks and a stairway connecting said front and rear floor portions, said stairway located opposite said side doorway.

8. A passenger car having a raised front floor portion and a low rear portion, a side doorway, the low rear floor portion being inclined from the side doorway and a stairway opposite said doorway connecting said floor portions.

9. A passenger car having trucks, a raised and a low floor portion, the raised portion being located over one of said trucks, a side doorway located opposite said side doorway, the low floor portion being inclined from the side doorway, a stairway connecting said floor portions, said side doorway being located between the trucks and adjacent one of them.

10. A passenger car having trucks, a raised and a low floor portion, the raised portion being located over one of said trucks, a side doorway at the low floor portion and within a single stepping distance of the ground,

the low floor portion being inclined from the side doorway, a stairway connecting said floor portions, said side doorway and said stairway being located between the trucks and adjacent one of them.

11. A passenger car having a raised floor portion and a low floor portion, a side doorway at the low floor portion and a stairway located opposite said doorway and connecting said floor portions, the low floor portion being inclined from the doorway.

12. A double deck passenger car having a raised floor portion and a low floor portion on the lower deck, a side doorway at the low floor portion, a stairway opposite said doorway connecting said floor portions and a stairway from said raised floor portion to the upper deck of the car.

13. A double deck passenger car having a raised floor portion and a low floor portion on the lower deck, a side doorway at the low floor portion, a landing at the raised floor portion, a doorway and door between said landing and the interior of the raised floor portion, a stairway connecting the low floor portion and the landing, and a stairway extending from the landing to the upper deck of the car.

14. A passenger car having a raised floor portion and a low floor portion, a side doorway at the low floor portion, a landing at the raised floor portion, a doorway and door between the landing and the interior of the raised floor portion, and a stairway connecting the low floor portion and the landing, said stairway being located opposite said doorway.

15. A passenger car having a raised floor portion and a low floor portion, a side doorway at the low floor portion, doors controlling the same, a stairway connecting the raised and low floor portions, said stairway located opposite said side doorway, and means located intermediate the side doorway and stairway for controlling the side door.

16. In a car, a floor having a portion depressed close to the track level to permit passengers to step directly onto the same, said floor being inclined away from said depressed portion, entrance and exit passageways at the depressed portion only of said floor, said car at all other points being normally closed against entrance and exit.

17. In a car, a floor having one end depressed below the level of a portion remote from said end, a platform supported at the depressed end thereof near the track level and arranged to permit a passenger to step directly from the street to the platform.

18. A car having its floor sloping toward one end thereof and having a portion at the lower end thereof arranged close to the track level, whereby passengers may step directly from the street onto the floor of the car.

- 4.
19. A car having its floor sloping toward one end thereof and having a portion of the lower end thereof arranged close to the track level and provided at said lower end with 5 both an entrance and an exit, whereby passengers may step directly onto or off of the floor of the car.
20. A car having two portions arranged at different levels and an inclined portion connecting the first-mentioned portions, the lower of said first-mentioned portions being arranged close to the track level to permit passengers to step from the street directly onto the same.
- 10 21. A street car having a boarding and alighting entrance at its front end and within a single step distance from the

ground, the floor level being inclined from said entrance to the rear end of the car, doors for controlling said entrance and 20 means for operating said doors.

22. A street car having a boarding and alighting entrance at one end within a single step distance from the ground, the floor of the car being inclined upwardly from the 25 entrance to the other end of the car.

In testimony whereof I have hereunto set my hand in the presence of the subscribing witnesses, on this 25th day of September, A. D. 1912.
